(57) **CLAIM**

The ornamental design for pipe repair clamp assembly as shown and described.

DESCRIPTION

1. Pipe repair clamp assembly
1.1 is an exploded view of a pipe repair clamp assembly showing my new design.
1.2 is a perspective view of one side of sleeve portion thereof;
1.3 is a perspective view of gasket portion thereof;
1.4 is another perspective view of gasket portion thereof;
1.5 is a perspective view of another side of sleeve portion thereof;
1.6 is an elevation view of clamping nut portion thereof;
1.7 is another elevation view of clamping nut portion thereof;
1.8 is a perspective view in an assembled state
1.9 is a front view in an assembled state
1.10 is a back view in an assembled state
1.11 is another perspective view in an assembled state
1.12 is a perspective view of gasket portion thereof;
1.13 is another perspective view of gasket portion thereof;
1.14 is an end view of gasket portion thereof;
1.15 is a perspective view of sleeve portion thereof;
1.16 is another perspective view of sleeve portion thereof;
1.17 is a perspective view of clamping nut portion thereof;

(Continued)

1.18 is another perspective view of clamping nut portion thereof;

1 Claim, 18 Drawing Sheets
